LIGHT SENSITIVE TUBE

Heinrich Geffcken, Hans Richter, and Karl Möller, Leipzig, Germany, assignors, by mesne assignments, to Radio Corporation of America, New York, N. Y., a corporation of Delaware

Application March 14, 1933, Serial No. 660,640
In Germany March 14, 1932

5 Claims. (Cl. 250—27.5)

Our invention relates to improvements in photoelectric tubes and methods of making such devices, particularly those having electrodes consisting of a metallic base coated with a layer of light sensitive material.

5 The underlying problem in the manufacture of photoelectric devices, as is known in the art, resides in the production of a light sensitive layer or film of high electron emitting properties. This is accomplished by a decrease of the electron affinity of the light sensitive layer or the work which must be performed in order to move electrons out through the surface of the layer into the surrounding space, and furthermore by an 10 increase of the electron emission produced by incident light of given intensity.

20 Layers of this type have a very low electron affinity with correspondingly increased emitting properties. However, the emission current is still very low in the photoelectric devices of this type known in the art.

25 Accordingly, it is an object of the present invention to provide a photoelectric device preferably of the composite layer type in which the emission is increased by a multiple as compared with similar devices known in the prior art.

30 Photoelectric tubes frequently are filled with a suitable gas such as a noble gas resulting in a highly increased sensitivity and increase of the emission current. A major disadvantage, however, of gas filled photoelectric tubes consists in an early destruction of the sensitive cathode layer due to bombardment by positively charged particles produced by ionization of the gas.

35 Accordingly, it is a further object of the invention to provide a new light responsive electrode which is highly insensitive against bombardment by positive ions.

40 According to the invention, a metallic base serving as a support for the light sensitive layer is used which has been subjected to a chemical or mechanical roughening process before the light sensitive layer is applied. The novel characteristics of a photoelectric electrode according to the 45 invention may be generally described as involving a surface of the base or supporting metal of the light sensitive layer which, when looked at, is formed with relatively minute or microscopic projections or depressions as distinguished from an ordinary smooth surface as used in photoelectric devices known in the prior art.

50 By using an unsmooth or roughened surface of sponge-like or velvet-like characteristics, according to the invention as set forth, a substantially increased chemical activity is secured, resulting

5 in highly increased photo-chemical properties of the light sensitive layer. Furthermore, a more substantial and uniform light sensitive layer is secured, uniformly covering the entire surface as compared with smooth light sensitive layers according to the prior art in which the sensitivity is highly irregular on different points over the surface.

10 When applying a light sensitive layer to an unsmooth or roughened surface in accordance with the invention, the layer will closely adhere to and follow the depressions or projections of the surface, resulting in an increased mechanical strength and uniform texture of the layer becoming less sensitive against mechanical shocks 15 and other disturbances tending to impair its photoelectrical properties as compared with a similar layer applied to a substantially smooth surface. This obviously furthermore accounts for the highly increased favorable properties of 20 light responsive electrodes, according to the invention.

25 A further advantage of light responsive electrodes, according to the invention, consists in an additional decrease of the electron affinity, due 30 obviously to the great uniformity and strength and uniform texture of the light sensitive layer obtained upon a rough or unsmooth surface.

35 The following practical example demonstrates the advantages and novel effects when using the new method according to our invention in producing photoelectric devices as described.

According to the method of the present invention using a roughened or velvet-like silver base, a dark brown layer is obtained having a 40 cathode drop from 80 to 100 volts and an emission in a vacuum tube of 18 to 25 microamperes per lumen.

45 It has already been proposed to artificially increase the all-over surface of light sensitive electrodes by forming artificial projections or depressions on the electrode surface. This procedure, however, was employed to afford a macroscopic increase of the all-over area and to produce point discharge effects, and is basically differentiated from the new method in accordance with the invention involving a roughening of the surface, resulting in more or less regular minute irregularities or depressions and projections, to produce an increase in chemical activity of the 50 metallic base metal or intermediate layer, respectively.

55 A roughened unsmooth surface of the base metal, as proposed by the invention, may be produced mechanically by a sandblasting treatment

or by a shaking operation with a suitable material, preferably obtained as a precipitate in a liquid mixture. Alternatively, an electric method may be employed, such as a dusting-off process 5 of metallic articles. Furthermore, a roughened or unsmooth surface may be produced by an etching process or by applying a rough coating to the metallic base. Another way consists in employing a chemical treatment consisting in first 10 transforming the surface of the metallic base into a chemical compound, decomposing such compound into the metal, and easily removable preferably gaseous components. In this case the roughening process may be carried out simultaneously 15 during the production of the base metal layer. The more velvet-like and chemically active the unsmooth or roughened surface in accordance with the invention, the greater will be the novel effects obtained.

20 Viewing the invention from another aspect, an explanation of the new increased photoelectric effects may be accounted for by the particular space charge conditions prevailing in a device of the type according to the invention. As 25 may be understood, considerable space charges will be formed within the depressions of the roughened surface, resulting in an "adherent space charge layer" closely covering the entire light sensitive surface. Now, it is well known that 30 by using thick oxide intermediate layers in composite tubes of the type under discussion, considerably increased emission currents may be obtained, but the thus obtained layers are very easily and shortly destroyed by the ionic bombardment, thus making this type of cathode structure 35 entirely unsuited for use in gas filled light sensitive tubes. By using electrodes with a roughened base surface, however, the above disadvantage is completely eliminated, making it possible to provide intermediate oxide layers of substantial 40 thickness, resulting in correspondingly increased electron emission as compared with a smooth base metal surface as used in the prior art. This effect is obviously due to a damping or cushioning 45 action of the adherent space charge layer covering the light sensitive surface and serving as a protection therefor against impinging ionic particles.

50 The invention will be specifically described in connection with the accompanying drawings, wherein;

Figure 1 is a schematic view showing a photoelectric device embodying a cathode or light sensitive electrode as shown by Figure 1.

55 Figure 2 shows a greatly enlarged cross-section of a roughened cathode surface with a light sensitive layer applied thereon in accordance with the invention. Figure 3 illustrates in cross-section a photoelectric tube according to the invention provided with a filter for preventing the objectionable influence of short wave length radiation upon the cathode.

60 An example of producing a light sensitive or cathode electrode by a chemical method in accordance with the invention is carried out as follows: Referring to Figure 1 of the drawing; the light sensitive device comprising in the usual manner a glass bulb 14 including a wire-shaped anode 16 and a cathode sheet 15, preferably of silver, 65 is connected to a high vacuum pump for evacuation. The electrodes 15 and 16 are shown to be connected to contact pins 18 and 19, respectively, mounted to a base 17 of the tube 14. After the tube has been evacuated, oxygen is introduced 70 under low pressure and a glow discharge started 75

between the electrodes in accordance with a well-known process whereby the silver sheet 15 is covered with an oxide coating. Subsequently, the tube is heated close to its softening temperature in such a manner that the oxide coating on the 5 sheet 15 is again decomposed, leaving a roughened or sponge-like surface on the silver electrode. Then the tube is processed and finished in the usual manner; that is, oxygen is again introduced, the electrode surface oxidized, the oxygen removed, and an alkali metal is introduced in vapor form and deposited to form a light sensitive film. Afterwards a noble gas may be introduced and the tube sealed up. The distinguishing and novel step resides in the first oxidizing 10 process and subsequent reduction, resulting in the production of an unsmooth or sponge-like surface of the silver base metal.

Instead of producing an oxide with subsequent reduction, any other chemical compound may be 20 produced and subsequently decomposed, such as chloride, bromide, or sulphur compound, and the like, for obtaining a roughened surface of the base metal.

25 Experiments have shown that the photoelectric sensitivity in gas filled photoelectric tubes having an average of about 50 microamperes per lumen may be increased by using electrodes according to the invention to more than about 100 microamperes per lumen.

30 The best gas filled tubes produced according to our invention have an output of 500-800 microamperes per lumen, a sensitivity of 300 microamperes per lumen being sufficient for most practical uses.

35 Furthermore, we have discovered that extremely sensitive photoelectric layers constructed according to our invention are destroyed by blue, violet and ultraviolet rays. It appears that this effect is due to a photochemical decomposition 40 of the unstable and complicated chemical compounds forming a composite photoelectric sensitive layer of this type. To avoid this drawback we provide an envelope non-permeable for such an objectionable radiation such as an envelope 45 of a brown-red colour. Such an envelope may consist of a colored glass bulb, used for manufacture of the tube itself or it may consist of a metal envelope having a coloured glass window; but we prefer to use normal glass bulbs for the production 50 of the tubes, in which case the production of the light sensitive layer is carried out in a room illuminated by red light only. The bulbs are then coated with a brown-red cellulose—or other varnish absorbing all wave lengths shorter than 55 about 5,500 A. U. or Angström units, that is the range comprising the lower portion of the visible spectrum (blue and violet rays) and the ultraviolet range below the visible spectrum.

60 (1 A. U.= 10^{-10} metre).

By these means the sensitivity of the tube is only reduced about 15-20%, but is remaining constant over an extremely long period.

65 By using the sensitivity destroying effect of short wave length rays we have been able to manufacture photo-electric bulbs of exactly prescribed sensitivity. For this purpose the bulbs are made with an extremely high sensitiveness and before laquering, are exposed to the rays of a 70 quartz-mercury or a metal salt arc lamp. Preferably the tubes are placed during this process in a chamber having two windows alternately opening, the first of which is arranged opposite to a standard carbon incandescent lamp, the 75

other being opposite said arc lamp. By alternately opening and closing said windows that is alternately measuring the output current produced by a standard illumination and desensitizing the photoelectric layer, an exactly predetermined value of sensitivity is easily attained. The tube is afterwards lacquer coated in the described manner, and by these means the attained sensitivity is maintained for an extremely long period. Further corrections may be made by suitably choosing the thickness of the varnish coating.

Referring to Figure 3 numeral 20 represents a glass bulb containing the light sensitive layer 21 deposited upon the inner wall of the bulb in the usual manner, and an anode in wire form shown at 22. The line 23 represents the lacquer film, used according to our invention and retaining objectionable rays such as blue, violet and ultra-violet rays liable to destroy the sensitive layer 21.

Referring again to Figure 2, the dimension of which is greatly exaggerated as regards the thickness of the layers, 10 represents the base metal such as a silver sheet as described, upon which there are formed projections 11 of minute dimension to secure a velvet-like or sponge-like surface. The surface is then covered with an intermediate layer 13, such as an oxide of the base metal as described, and the intermediate layer coated in turn with a light sensitive layer 12 as shown.

Besides the described and illustrated modification, the invention, of course, is capable of other variations and modifications within its scope, and may be embodied in other styles or types of photoelectric devices. The photoelectric layer may be of any suitable composition and produced by any desired process applied either directly to the base metal or in conjunction with an intermediate layer as described.

40 We claim:

1. The method of adjusting the emission cur-

rent during the manufacture of photo-electric tubes consisting in subjecting the light sensitive electrode to the influence of short wave length radiation of the lower visible and the ultra-violet range of definite intensity and over a definite period.

2. A photoelectric tube comprising a light sensitive negative electrode of the composite layer type and a cooperating positive electrode included in a vessel and a light filter for preventing radiation of the lower visible and of the ultra violet range from effecting the light sensitive electrode.

3. A photoelectric tube comprising a cathode electrode having a highly light sensitive surface of the composite layer type and a cooperating positive electrode included in a vessel and a light filter disposed closely to said tube and adapted to prevent short wave length radiation of the lower visible and of the ultra-violet range from effecting said light sensitive surface.

4. A method of adjusting the emission current of photo-electric tubes having a composite layer type light sensitive emissive surface consisting in subjecting the light sensitive surface to the influence of ultra-violet radiation of predetermined intensity until the desired emission is obtained.

5. A photoelectric tube comprising a vessel, a negative electrode therein having a composite light sensitive layer, a co-operating positive electrode in said vessel, said vessel being provided with a window for passing controlling light rays to said cathode and a coating of red-brown coloring lacquer applied to said window for preventing ultra-violet rays and rays of the lower part of the visible spectrum from effecting the said light sensitive layer.
